UNITED STATES PATENT OFFICE.

JOHN QUINCY BOSELLEMAN, OF PHILADELPHIA, PENNSYLVANIA.

DISPENSING-CAN.

1,243,801.

Specification of Letters Patent. Patented Oct. 23, 1917.

Application filed August 5, 1916. Serial No. 113,249.

To all whom it may concern:

Be it known that I, JOHN Q. BOSELLEMAN, a citizen of the United States, residing at Philadelphia, in the county of Philadelphia, 5 and State of Pennsylvania, have invented certain new and useful Improvements in Dispensing-Cans, of which the following is a specification.

My invention consists of improvements 10 in dispensing cans, one object being to provide an improved mounting for a diaphragm pump which permits ready access to the diaphragm and check valves whenever desired to inspect the same or make repairs.

15 A further object is to provide an improved spring-held pivoted spout which in its closed position is resiliently held against the pump handle in such manner as to prevent the operation of the handle, and which 20 when in such position entirely cuts off the outlet.

A further object is to provide a dispensing can with a pivoted spout which is held in both of its normal positions by an improved construction and arrangement of spring, and which is in open communication with the outlet pipe of the can when in one extreme position, and cuts off the outlet in its other extreme position, the said 25 30 spring operating to compel the spout to rest in either of its extreme positions, so that it is impossible to leave the spout in an intermediate position.

These objects, and other advantageous 35 ends which will be described hereinafter, I attain in the following manner, reference being had to the accompanying drawings in which

Figure 1 is a plan view illustrating my 40 improved dispensing can.

Fig. 2 is a sectional plan view on an enlarged scale illustrating the spring for controlling the position of the spout.

Fig. 3 is a view in section on the line 3—3 45 of Fig. 1.

Fig. 4 is a fragmentary view in section on the line 4—4 of Fig. 1.

Fig. 5 is an enlarged fragmentary detail view on the line 5—5 of Fig. 1.

50 Fig. 6 is a view of similar nature to Fig. 3 showing a different construction of the pump mounting, and

Fig. 7 is a fragmentary elevation of a different form of nozzle coupling.

Considering Figs. 1 to 5 inclusive, my 55 improved dispensing can 1 has an inlet 2 in its top 3, said inlet being provided with a spring-pressed check valve 4 to permit air to enter the can as the contents are dispensed.

60 On the top 3, I secure the lower member 5 of a pump casing 6. This lower member 5 is preferably made cylindrical in form, and at its upper edge is made with an annular flange 7.

65 The upper section or half 8 of the pump casing 6 is provided with an annular flange 9, corresponding with flange 7, and 10 is a diaphragm clamped between the flanges 7 and 9.

70 I have illustrated in Figs. 1 to 5 inclusive of the drawings, one of my means for clamping the two pump casing sections together, which consists of a plurality of tongues 11, integral with the flange 9, and 75 bent under flange 7, but I may, of course, resort to other forms of removably securing the upper pump section 8, as for example in Fig. 6, as will hereinafter be described, so that the section 8 can be removed as occasion may require.

70 A check valve 12 is positioned in the top 3 and communicates with the pump casing, and 13 is a check valve in a diaphragm which controls the flow of air through the dia- 85 phragm.

80 A stem 14 is secured to the diaphragm 10, and projects through an opening 15 in the top of the pump casing section 8, and is preferably provided with a shield 16 above 90 said opening.

85 A pump handle 17 is pivotally supported on a removable pin 18, in a bracket 19, on the casing section 8, and at its free end bends downwardly as shown at 20. The pump 95 handle 17 extends through an opening 14^a in the stem 14, so that the pivotal movement of the handle operates to reciprocate the stem and move the diaphragm.

90 An outlet pipe 21 extends through the top 100 3, and terminates close to the bottom 22 of can 1. The upper end of the outlet pipe 20 is preferably tapered as shown, and is closed at its top as indicated at 23. This pipe is provided at one side with an outlet opening 24.

100 A spout 25 has an integral sleeve 26 or cap mounted to turn on the upper end of

pipe 21, and adapted to cut off the outlet opening 24 except when the spout is in a position extended over the side of can 1. The spout 25 is held in its normal positions by means of a spring 27. This spring 27 is mounted in a housing 28, pivotally connected at one end as shown at 29, to the pump casing section 8.

The spring 27 consists of a single piece of 10 spring wire coiled at four different points as shown at 30, and connected at one end to a rod 31 which extends through eyes 32 in the spring, and through an opening 33 in the end of housing 28. This rod 31 has an 15 eye 34 at its free end, which engages over a pin 35 on spout 25, and operates to hold the spout in its open and closed positions.

When the spout is in closed position, the 20 spring operates to hold the same against the curved end 20 of pump handle 17 and operates to prevent any movement of the handle, while the spout is in its closed position.

When the spout is swung to open position, 25 the rod 31 is moved longitudinally, causing the spring 27 to contract as shown in dotted lines in Fig. 2, and it will be noted that when the spout swings past a line extending through the axis of the nozzle, the 30 spring will again expand, and compel the spout to move to its extreme open position, where opening 24 in pipe 21 registers with the spout.

In other words, the spring 27 prevents the 35 spout from remaining at any intermediate position, but compels the same either to be entirely open or closed, and when closed prevents or interferes with the operation of the handle 17.

40 In the form of valve casing shown in Fig. 6, the cover 36 has its sides 37 arranged in frusto-conical form tapering upwardly and has its lower edge portion 38 bent to form an annular groove 39. A ring 40 has 45 a base flange 41 which is secured to the top 3 of the can, and has a curved upper edge portion 42 upon which the diaphragm 43 rests, the edge portion of said diaphragm extending between the edge portion 42 and the 50 internal surface of the side portions 37.

A ring 44 is secured to the ring 40, and has an outwardly projecting annular flange 45 which fits within the groove 39.

The can 1 including the top 3 and the 55 other portions are substantially identical to the other members shown in Fig. 3, and I have therefore given the same like reference numerals.

The lower edge of the loop portion 38 60 comprises a plurality of tongues 38a which when it is desired to remove the cover 36, may be bent downwardly to free the flange 45 of the ring 44.

It will be further noted that by making 65 the sides 37 of the cover 36 tapered, a tight

clamping action can be had for the dia- phragm 43.

In Fig. 7, the outlet pipe 46 has an upwardly tapering frusto-conical sleeve 47 which is provided with an outlet opening 70 48. This sleeve is provided with a rotatable frusto-conical cap 42 which has secured to and intersecting with it, a spout 50.

The upper portion of the cap is provided 75 with a beaded top 51 into which is secured one end of a spiral tension spring 52, the other end of said spring being secured to a transverse rod 53 mounted in the pipe 46. The cap 42 closely fits the sleeve 47 and may be rotatable in a similar manner to the 80 pipe 25 so as to bring its passage in line with the opening 48 to permit the contents of the can 1 to be dispensed.

While I have described my invention as 85 taking a particular form, it will be understood that the various parts of my invention may be changed without departing from the spirit thereof, and hence I do not limit myself to the precise construction set forth, but consider that I am at liberty to make such 90 changes and alterations as fairly come within the scope of the appended claims.

Having thus described my invention, what 95 I claim as new and desire to secure by Letters Patent is:

1. The combination with a can having a pump thereon, and a pivoted pump handle, of an outlet pipe communicating with the can and having an outlet opening in its side, a spout having portions extending into and 100 out of said can, said outwardly projecting portion having a cap at one end mounted to turn on the outlet pipe and adapted when in one extreme position to communicate with the outlet opening, and a spring holding the spout in its open and closed positions, the spout when in said closed position extending across the path of movement of the pump handle to prevent operation thereof, substantially as described. 110

2. The combination with a can having a pump thereon, of an outlet pipe having an opening therein and communicating with the can, a spout pivotally supported on the outlet pipe, a housing pivotally connected 115 to the pump casing, a spring confined in said housing, and a rod connecting said spring with the spout, said spring operating to hold the spout in either of its extreme positions, and said spout when in one of said 120 extreme positions communicating with the opening in the outlet pipe and when in the other of its extreme positions cutting off said opening, substantially as described.

3. The combination with a can having a 125 pump thereon, and a pivoted pump handle, of an outlet pipe having portions projecting into and out of said can, an outwardly tapering frusto-conical sleeve on said out- 130 wardly projecting portion of said pipe and

having an opening in its side, a spout having a frusto-conical cap rotatably fitting said sleeve, and resilient means for holding said cap and sleeve together and to take up for wear which might occur between them, substantially as described.

In testimony whereof I have signed my

name to this specification in the presence of two subscribing witnesses.

JOHN QUINCY BOSSELMANN.
